(57) **CLAIM**

We claim the ornamental design for a combined breeder box and panel assembly, as shown and described.

DESCRIPTION

FIG. 1 is a left, front perspective view of a first embodiment of a combined breeder box and panel assembly shown according to the present design;

FIG. 2 is a right, rear perspective view thereof;

FIG. 3 is a front end view thereof;

FIG. 4 is a rear end view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a left, front perspective view of a second embodiment of a combined breeder box and panel assembly shown according to the present design;

FIG. 10 is a right, rear perspective view thereof;

FIG. 11 is a front end view thereof;

FIG. 12 is a rear end view thereof;

FIG. 13 is a left side elevational view thereof;

FIG. 14 is a right side elevational view thereof;

FIG. 15 is a top plan view thereof; and,

FIG. 16 is a bottom plan view thereof.

The broken lines in the figures illustrate portions of the combined breeder box and panel assembly that form no part of the claimed design.
